DESIGN FOR A COOKING RANGE

Fredrick David Chapman, Chicago, Ill., assignor to Montgomery Ward & Co., Incorporated, Chicago, Ill., a corporation of Illinois

Application December 23, 1935, Serial No. 60,248

Term of patent 7 years

To all whom it may concern:

Be it known that I, Fredrick David Chapman,
a citizen of the United States, residing at Chicago,
in the county of Cook and State of Illinois, have invented a new, original, and ornamental Design for a Cooking Range, of which the following is a specification; reference being had to the accompanying drawing, forming a part thereof.

In the drawing, the figure is a perspective view
of a cooking range showing my new design.

The side of the range which is not seen is substantially plain.

I claim:

The ornamental design for a cooking range, as shown and described.

FREDRICK DAVID CHAPMAN.
